TANK TRAILER FOR A MARKING MACHINE FOR HIGHWAYS AND THE LIKE

Carl L. Fry, Lycoming County, Pa., assignor to Wald Industries, Inc., Huntingdon, Pa., a corporation of Pennsylvania

Filed Mar. 31, 1961, Ser. No. 64,567

Term of patent 14 years

(Cl. D14—3)

FIG. 1.

FIG. 2.

FIG. 4.

FIG. 3.

FIG. 5.

FIG. 1 is a perspective view of a tank trailer for a marking machine for highways and the like showing my new design with portions shown in broken lines for illustrative purposes only.

The dominant features of the design reside in the portions shown in full lines.

I claim:

The ornamental design for a tank trailer for a marking machine for highways and the like, as shown and described.
